Primary Examiner — Paula Greene(74) *Attorney, Agent, or Firm* — Jianq Chyun IP Office(57) **CLAIM**

The ornamental design for a mass microscope, as shown and described.

DESCRIPTION

FIG. 1 is a perspective view of a mass microscope showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portions of the mass microscope present unclaimed portions of the claimed design and form no part thereof.
